US0D1065166S

(12) **United States Design Patent** (10) **Patent No.:** **US D1,065,166 S**
(45) **Date of Patent:** **** Mar. 4, 2025**

(54) **CASE FOR ELECTRONIC COMMUNICATION DEVICE**

(71) Applicant: **SHENZHEN GUANGYIPENG TECHNOLOGY CO., LTD.,**
Guangdong (CN)

(72) Inventor: **Jie Weng**, Guangdong (CN)

(73) Assignee: **Shenzhen Guangyipeng Technology Co., Ltd.**, Shenzhen (CN)

(**) Term: **15 Years**

(21) Appl. No.: **29/894,152**

(22) Filed: **Jun. 7, 2023**

(51) LOC (15) Cl. **03-01**

(52) U.S. Cl.

USPC **D14/250**; D14/253

CLAIM

The ornamental design for a case for electronic communication device, as shown and described.

DESCRIPTION

FIG. 1 is front, left, and top perspective view of a case for electronic communication device showing my new design; FIG. 2 is rear, right, and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is another perspective view of the case for electronic communication device of FIG. 1, shown with additional environmental structures; FIG. 10 is another perspective view of the case for electronic communication device of FIG. 9, shown in an alternate configuration; and, FIG. 11 is another perspective view of the case for electronic communication device of FIG. 1, shown in an alternate configuration. The broken lines in the drawings represent portions of the case for electronic communication device or environmental subject matter that form no part of the claimed design.

1 Claim, 11 Drawing Sheets
